ILLUMINATED PANEL

Howard A. Thompson, Edgewood Borough, Pa., assignor to The Union Switch & Signal Company, Swissvale, Pa., a corporation of Pennsylvania

Application December 12, 1929, Serial No. 413,580

9 Claims. (Cl. 177—311)

My invention relates to illuminated panels, and particularly to panels in which a plurality of bull's-eyes or other similar devices located on the front of the panel are illuminated by means of light units located back of the panel.

One object of my invention is to provide means for transmitting light from the light units to the bull's-eyes in such manner that each light unit may be located at a point remote from the associated bull's-eye, thereby enabling the use of smaller bull's-eyes, and permitting the closer spacing of bull's-eyes, than would be possible if each light unit were located directly back of the bull's-eye which it illuminates.

I will describe one form of illuminated panel embodying my invention, and will then point out the novel features thereof in claims.

In the accompanying drawing, Fig. 1 is a top plan view of one form of illuminated panel embodying my invention. Fig. 2 is a sectional view on an enlarged scale of a portion of the illuminated panel shown in Fig. 1.

Similar reference characters refer to similar parts in both views.

Referring to the drawing, the reference character A designates a panel, preferably of insulating material, which as here shown, is of the type customarily employed in railway signaling practice and which is usually termed a "track model". This panel is provided with a diagram representing two parallel sections of railway track B—C and D—E connected by a crossover F. Panel A is also provided with a representation of the signals S and L which govern traffic moving from right to left over the sections of railway track represented in Fig. 1.

Associated with the representation of section B—C on panel A is a bull's-eye 1 which may at times be illuminated, in a manner to be described in detail hereinafter, to indicate traffic conditions in section B—C, and associated with the representation of section D—E is a similar bull's-eye 2 which serves a similar purpose. Two other bull's-eyes 3 and 4 are located on panel A at the right-hand end of the representation of crossover F, and two similar bull's-eyes 5 and 6 are located at the left-hand end of the representation of crossover F. The bull's-eyes 3, 4, 5, and 6 serve to indicate the condition of the switches 50 associated with crossover F and, as here shown, are made rectangular in order that they can be distinguished readily from the bull's-eyes which indicate traffic conditions in sections B—C and D—E and which are round. By way of illustration, I will assume that bull's-eye 3 becomes il-

luminated when the switch at the right-hand end of crossover F is normal, that is, set for traffic to proceed along section B—C past this switch, and that bull's-eye 4 becomes illuminated when this switch is reversed. In similar manner, I will assume that bull's-eye 5 becomes illuminated when the switch at the left-hand over crossover F is normal so that traffic can proceed along section D—E past this switch, but that bull's-eye 6 becomes illuminated when this latter switch is reversed.

The representation of signal S consists of a left-hand group J of bull's-eyes comprising three bull's-eyes 7, 8 and 9, a middle bull's-eye 10, and a right-hand group K of bull's-eyes comprising two bull's-eyes 11 and 12. The representation of signal L comprises two bull's-eyes 13 and 14. Different ones of these bull's-eyes which make up the representations of the signals S and L may be illuminated in accordance with the different indications displayed by signals S and L.

For illuminating the bull's-eyes, I provide a plurality of light units each designated by the reference character P with an exponent corresponding to the reference character of the bull's-eye which it illuminates. These light units may be of any suitable type but, as here shown, they are all similar to the light unit P¹⁰ shown in Fig. 2. This unit comprises a receptacle 25 attached to a suitable support 23 and provided with an electric lamp 24 which may, for example, be a standard telephone switchboard lamp. The light units may be controlled in any suitable manner, forming no part of my invention, and therefore not shown in the drawing.

It is desirable that the bull's-eyes should be small and should be placed close together in order that panel A may be made as small as possible. With the commercial sizes of light units available, however, when the bull's-eyes are small and are placed close together, there is insufficient room to mount the light units directly back of the bull's-eyes, as is ordinarily done, and I therefore propose to mount the light units at the most convenient location and to transmit light from the light units to the bull's-eyes by means of light transmitting members. For this purpose, I provide the panel A at each point where it is desired to locate a bull's-eye with a hole similar to the hole 19 shown in Fig. 2 and with a groove 20 which extends from such hole 19 to a point adjacent the associated light unit. The light transmitting members for each bull's-eye are mounted in the associated hole 19 and groove 20 and, as here shown, comprises three

glass rods 15, 16, and 18, the outer surfaces of which with the exception of their ends are covered with light reflecting means such, for example, as the standard silver deposit commercially employed in mirrors.

Each of the rods 15 and 18, as here shown, is substantially L-shaped and, if desired, may be made similar for each bull's-eye to be illuminated. The rods 16, however, will have different lengths depending upon the distance between the associated bull's-eye and light unit. The rods 15, 16 and 18, are held in place in the grooves 20 and holes 19 by an auxiliary panel N, fastened to the back of the panel A in any convenient manner, and provided with suitable holes which receive the legs 15^b of the L-shaped rods 15. The light units are so arranged that the leg 15^b of the L-shaped rod 15 associated with each bull's-eye enters the receptacle 25 of the light unit P for that particular bull's-eye. It will be apparent therefore that when the lamp 24 of a light unit P is illuminated, light rays will enter the lower end of the leg 15^b of the associated L-shaped rod 15.

The bull's-eyes may be separate members of any suitable type, which fit into the holes 19 over the upper ends of the legs 18^c of the L-shaped rods 18, or they may be formed directly on the ends of the legs 18^c as shown in Fig. 2. Furthermore, they may be either round or square, as pointed out hereinbefore, and, if desired, they may be provided with a plurality of light refracting prisms.

The operation of the light transmitting members 15, 16 and 18 will best be understood by referring particularly to the members 15, 16 and 18 which receive light from lamp 24 of the light unit P¹⁰ shown in Fig. 2. Here it will be seen that the light rays which enter the end of the leg 15^b of the rod 15 associated with light unit P¹⁰ from the lamp 24 of unit P¹⁰ are transmitted through this leg 15^b to a surface 15^c which is normal to the bisector of the angle made by the axes of legs 15^a and 15^b of the rod 15 and passes through the point of intersection of such axes. Since the surface 15^c is silvered, the light rays upon striking this surface are reflected along the axis of leg 15^a as shown by the dotted line 21. The deflected light rays then pass through the leg 15^a of rod 15, straight rod 16, and leg 18^b of rod 18, to the surface 18^c of rod 18. This latter surface extends normal to the bisector of the angle made by the axes of legs 18^a and 18^b of rod 18 so that the light rays upon striking this surface are again reflected along the axis of leg 18^a. The light rays therefore pass through leg 18^c of rod 18 to the associated bull's-eyes 10.

Under some conditions it is desirable to impart distinctive colors to the bull's-eyes, when illuminated, to aid an operator in distinguishing between the different bull's-eyes. This may be done by coloring the bull's-eyes or any of the associated glass rods, but as here shown, I prefer to accomplish this result by means of color screens 17, one of which may be interposed between each straight glass rod 16 and the leg 18^b of the associated glass rod 18.

Although I have herein shown and described only one form of illuminated panels embodying my invention, it is understood that various changes and modifications may be made therein within the scope of the appended claims without departing from the spirit and scope of my invention.

Having thus described my invention, what I claim is:

1. Apparatus for illuminating a small section of space which is of such size and in such close proximity to other similar sections of space that the direct application of a lamp to said section of space is impossible, said apparatus comprising a transparent glass rod having one end disposed adjacent said section of space and the other end located at a point remote from said section of space, and means for supplying light rays to said other end of said rod in such manner that said light rays will be transmitted through said rod to said section of space, the outer surface of said rod with the exception of its ends being covered with a silver deposit to form a light reflecting surface which aids the transmission of light rays through said rod. 5

2. Apparatus for illuminating a bull's-eye which is of such size and in such close proximity to other similar bull's-eyes that the direct application of a lamp to said bull's-eye is impossible, said apparatus comprising a source of light located at a point remote from said bull's-eye, a first transparent glass rod having one end adjacent said bull's-eye, and a second glass rod having one end receiving light rays from said source and the other end abutting against the other end of said first glass rod, the outer surfaces of said glass rods with the exception of their ends being provided with light reflecting means arranged to aid the transmission of light 10 through said rods. 20

3. Apparatus for illuminating a small section of space which is of such size and in such close proximity to other similar sections of space that the direct application of a lamp to said section of space is impossible, said apparatus comprising a source of light located at a point remote from said section of space, and one or more transparent rods arranged end to end to form a continuous light path from said source of light to said section of space, each said rod being provided on its outer surface with the exception of its ends with light reflecting means for improving the transmission of light through the rod. 35

4. Apparatus for illuminating a small section of space which is of such size and in such close proximity to other similar sections of space that the direct application of a lamp to said section of space is impossible, said apparatus comprising a source of light located at a point remote from said section of space, one or more transparent rods arranged end to end to form a continuous light path from said source of light to said section of space, each said rod being provided on its outer surface with the exception of its ends with light reflecting means for improving the transmission of light through the rod, and means for imparting a distinctive color to the light transmitted through said transparent rod or rods. 40 50

5. Apparatus for illuminating small sections of space which are of such size and in such close proximity that the direct application of lamps thereto is impossible; said apparatus comprising a plurality of sources of light, one for each section to be illuminated, and each located at a point remote from the section of space for which said source is provided; and separate means for transmitting light from each source of light to the section of space for which such source is provided, each said means comprising a plurality of glass rods arranged end to end, each said rod being provided on all of its outer surfaces but its ends with light reflecting means for improving the transmission of light therethrough. 60 65 70

6. In combination, a panel provided with a

track diagram corresponding to a railway track layout and with representations of switches and signals for governing traffic over said track layout, a plurality of bulls'-eyes associated with each 5 switch and signal and adapted to be selectively illuminated to indicate the condition of the associated switch or signal, said bulls'-eyes being of such size and in such close proximity that the direct application of a lamp thereto is impossible, and means for illuminating said bulls'-eyes comprising a plurality of sources of light, one for each bull's eye to be illuminated, and each located at a point remote from the bull's eye for which such source is provided, and one or more glass 10 rods associated with each source of light and arranged to form a continuous light path from such source of light to the bull's-eye for which such source of light is provided, each said rod being provided on its outer surface with light reflecting 15 means for improving the transmission of light through such rod.

7. A track model provided with a diagram of a portion of railway track, a plurality of bulls' eyes carried by said track model and each when illuminated representing a particular traffic condition with respect to said portion of track, said bulls' eyes having such size and location that the direct application of a light source thereto is im- 20

possible, a plurality of light sources one for each bull's eye but located remote therefrom, and light conducting means interposed between each bull's eye and its associated light source.

8. A track model provided with a diagram of a portion of railway track, a plurality of bulls' eyes carried by said track model and each when illuminated representing a particular traffic condition with respect to said portion of track, said bulls' eyes having such size and location that the direct application of a light source thereto is impossible, a plurality of light sources one for each bull's eye but located remote therefrom, and light conducting means formed of a transparent solid material interposed between each bull's eye and 15 its associated light source and carried by said track model.

9. A track model provided with a diagram of a portion of railway track and having small areas each when illuminated representing a particular traffic condition with respect to said portion of track, said areas having such sizes and locations that the direct application of lamps thereto is impossible, a plurality of lamps all located remote from said areas, and glass light conducting means 25 interposed between each such area and an associated one of such lamps.

HOWARD A. THOMPSON.
